Edmund G. Borden

UNITED STATES PATENT OFFICE.

BENJAMIN GREENFIELD, OF JACKSON HEIGHTS, NEW YORK, ASSIGNOR TO COMBUSTION UTILITIES CORPORATION, OF NEW YORK, N. Y., A CORPORATION OF MAINE.

LUBRICATING SYSTEM FOR AIR BLOWERS.

Application filed February 25, 1926. Serial No. 90,440.

This invention relates to a system for lubricating air blowers of the type having disk-like pistons mounted on eccentrics on a driving shaft. Blowers of this type are well adapted for use in connection with oil-burning house-heating systems because of their positive action and relative simplicity and when properly lubricated give efficient service over long periods of time. Present lubricating systems for this type of blower require attention at more or less regular intervals if the blower is to function efficiently.

It has been found, however, that the average householder cannot be relied upon to give regular attention to the proper lubrication of devices forming part of a house-heating system. It is therefore desirable that the matter of lubrication be made as easy as possible whereby to relieve the householder of constant attention to the lubrication of the blower.

The present invention has for its object to provide a lubricating system for air blowers of the type indicated which shall have an oil supply from which oil may be continuously drawn by the blower as it operates, such supply preferably being enough to provide all the oil needed for the season during which the house-heating system will be operated, whereby the householder may be relieved of frequent attention to the lubrication of the blower.

In accordance with the present invention, two oil reservoirs are provided, one of which may be termed a primary reservoir and the other a secondary reservoir. The primary reservoir is conveniently located within the blower housing and the second reservoir is conveniently formed in the base on which the blower unit is mounted. The primary reservoir feeds oil to the blower at a uniform rate, the oil being entered into the blower along with the intake air. The oil feeding device associated with the primary reservoir is so constructed that a constant oil level must be maintained in the reservoir in order to provide a constant rate of feed. In order to keep the primary reservoir constantly full of oil, means are provided for continuously withdrawing enough oil from the secondary reservoir to keep the primary reservoir full.

In the preferred embodiment of the invention the oil supplied to the primary reservoir from the secondary reservoir first passes through the blower along with the intake

air, the oil being separated from the outgoing air by an oil separator from whence it flows to the primary reservoir. When the oil from the secondary reservoir is supplied to the primary reservoir in the manner indicated, the rate of feed from the primary reservoir is so regulated that its rate of feed plus the oil fed from the secondary reservoir shall just be enough to thoroughly lubricate the blower without flooding it. Another feature of the invention is that upon starting the blower after a period of rest a slug of oil will be supplied to the blower whereby to give it a preliminary bath of oil.

For a fuller understanding of the invention reference is made to the following detailed description taken in connection with the accompanying drawings forming part of this specification.

Referring to the drawings

Fig. 1 is a view in vertical section of a combined motor-driven blower and oil pump showing the blower which is to be lubricated in accordance with the present invention, the housing within which the motor is contained being shown in elevation.

Fig. 2 is a vertical transverse section taken on line 2-2 of Fig. 1 and showing in detail the preferred form of the various features of the lubricating system.

Fig. 3 is a vertical transverse section taken on line 3-3 of Fig. 1 and showing among other things an oil separator which it is preferred to use in connection with the lubricating system of the present invention.

In the drawings, the blower to be lubricated is shown as part of a combined oil and blower unit driven by a common motor, the motor being generally indicated at 10, the blower at 12 and the oil pump at 14, the whole assembly being shown as supported on a hollow base 16 having an oil reservoir 18 therein after more fully referred to.

The blower construction includes two axially aligned cylinders 20 and 22, the adjacent ends of which are separated by plate 24 and the opposite ends of which are closed by plates 26 and 28 respectively, the oil pump, not necessary to be described, being located on the outer side of the plate 28. Extending from the outer face of the plate 26 is a hollow casing 30, the outer end of which abuts and is fixedly connected to the housing of the motor 10 in any suitable manner. Below said cylinders 20 and 22 are chambers 32 and 34

respectively, one for each cylinder, the chambers and cylinders being in open communication through a passage 36 (see Fig. 3).

The blower pistons take the form of relatively wide disks 38 of smaller diameter than their cylinders, there being one disk for each cylinder. These disks are mounted on a crank shaft 40 which extends through and has bearing in, the plates 26, 24 and 28, the shaft being coupled to the shaft of the motor 10 in any suitable manner as by a flexible coupling 42. The cranks or eccentrics of the shaft 40 are indicated at 44. The cranks 44 are lubricated through ports 46 extending radially through the disk pistons 38. Each piston is preferably made hollow and is provided with a crank-bearing bushing 48. The hollow portion of the piston forms a chamber in which the lubricating oil may accumulate for the better lubrication of their respective cranks. Each piston is prevented from rotating about its own axis by an arcuate member 50 one end of which is rockably connected to the cylinder casting as at 52 and the other end to the piston as at 54 at a point in line with the passage 36, the arcuate members being located within the said chambers, one member in each chamber. Each arcuate member 50 is as wide as its piston and divides the chamber in which it is placed into upper and lower parts, namely, into an air intake portion or side and an air outlet portion or side, the similar sides of both chambers being in open communication with each other through ports 56 and 58 extending through the cylinder-dividing plate 24 (see Fig. 3). The air intake sides of said chambers are open to the atmosphere through means including a port 60 in the plate 26, a conduit 62 which is in communication with said port and located within the chamber formed by the flange 30 projecting laterally from the cylinder plate 26, a conduit 64 located outside of the blower housing, and a foraminous sleeve or screen secured to the conduit 64. The air outlet sides of said chambers 32 and 34 are in open communication with a conduit 68 from whence the compressed air passes through an oil separator and from thence into a conduit 69 which leads to the oil burner or furnace (not shown).

The mode of operation of the blower will be readily understood from the foregoing description but may be briefly described as follows:

As the crank shaft 40 rotates the piston disks 38 mounted on the cranks of the driving shaft 40 are caused to wipe their cylinders, the intake air entering the cylinders through a path including that part of the passage 36 on the concave side of the arcuate members 50, the compressed air passing from the cylinders through the other half of the passage 36 and the conduits previously mentioned.

The mechanism for lubricating the above described blower construction will now be explained. An oil reservoir generally designated at 70 is formed in the laterally extending casing 30 by means of an upright wall 72 therein. This reservoir for convenience of description may be termed the primary reservoir. The oil reservoir 18 previously described as being formed in the hollow base 16 is preferably located immediately below the reservoir 70 and may be termed the secondary reservoir. When the reservoir 70 is full to overflowing, it overflows through a standpipe 74 into the reservoir 18.

Disposed within the primary reservoir 70 is an oil-feeding device generally indicated at 76. This device comprises a body having a relatively small bore 77, the lower end of which is open to the reservoir 70 as through a laterally extending opening 77', in the body near its bottom and the upper end of which opens into an oil well 78. The top of the bore 77 is below the top of the overflow pipe 74. Consequently oil will accumulate in the oil well to a level as high as the top of the pipe 74 when the reservoir is full of oil. Extending from the top of the oil well is an open-top pipe 79 through which air may be blown for cleaning out the bore 77 when required. The top of this pipe terminates near the top of the blower housing, the latter having an opening 96 therein normally closed by a cover 98 whereby access may be had to the pipe. Leading from near the bottom of the oil well 78 is a pipe 82 which is in open communication with the air intake conduit as at the branch 62 thereof. The suction produced in the air intake conduit when the blower is operating is sufficient to draw the oil flowing into the oil well into the ingoing current of air. When the blower is first started a slug of oil representing the accumulated oil in the oil well will be drawn into the blower by the ingoing air thus giving the blower a preliminary bath of oil. It may be mentioned at this point that the suction effective in the pipe 82 does not exert any effect on the rate of feed of oil through the bore 77 inasmuch as the oil well is open to the atmosphere through the pipe 79.

In order to economize on oil the outgoing air is relieved of the oil carried thereby or suspended therein by passing the air through any approved form of oil separator. The oil separator shown in the drawings (Fig. 3) comprises a drum 86 into which extends a closed-top tube 84 having radial openings 88 below the tube top, said tube extending from the outlet of the air conduit 68. The oil laden air passes through radial openings 88 and impinges against the sides of the drum with the result that the oil is precipitated by the walls of the drum and collects in the bottom of the drum from which it is drawn through a pipe 94 emptying into the pre-

liminary reservoir 70 (see Fig. 2). The air relieved of its oil passes out of the drum through the opening 90 in the top thereof from whence it passes into the pipe 69 leading to the oil burner or furnace (not shown).

Oil from the oil reservoir 18 is fed to the primary reservoir 70 in the following manner. Within the reservoir 18 is formed a relatively small oil chamber 91 into which dips a pipe 93 leading from the air intake conduit as from the branch 64 thereof. Oil is fed into this chamber by a wick 95 looped over a partition 97 which separates the chamber from the main reservoir. The oil feeding capacity of the wick is such that only enough oil will be fed by the wick into the chamber 91 to insure that the primary reservoir 70 shall always be maintained full of oil. The oil accumulating in the chamber 91 is drawn up through the pipe 93 by the ingoing air and passes through the blower in the same manner as the oil being fed from the primary reservoir 70. As previously indicated the outgoing air passes through an oil separator and the oil accumulating therein flows to the primary reservoir by way of the pipe 94 leading from the drum 86 forming part of the oil separator. As previously indicated any surplus oil in the primary reservoir 70 returns to the reservoir 18 through the overflow standpipe 74. The chamber 91 is open to the atmosphere by way of a small hole 98 in the reservoir wall and consequently the rate of feed of the wick 95 is not affected by the suction in the pipe 93. Inasmuch as the wick will continue to feed oil into the chamber 91 irrespective of whether or not the blower is operating, a small quantity of oil will accumulate in the chamber 91 when the blower is not operating. Upon starting the blower this accumulated oil will be drawn up through the pipe 93 as a slug of oil and will serve to give the blower a preliminary bath of oil. It will be remembered that a slug of oil was also taken from the oil well 78 upon starting the blower after a period of rest.

It will now be appreciated that the invention provides two distinct lubricating systems but which are, nevertheless, so related that the operation of both is necessary for the thorough lubrication of the blower. The oil feeding device in the reservoir 18 while its primary purpose is to supply sufficient oil to the reservoir 70 to maintain it full at all times, nevertheless, also functions to supply a certain amount of direct lubrication to the blower.

While the primary oil feeding device 76 has been shown as provided with a straight upright bore 77, it is within the spirit of the invention to regulate the flow of oil through a bore or passage which is not necessarily straight. For example, the bore might be made in the form of a spiral in which event

the bore could be made of a larger cross-sectional area inasmuch as the greater length of the bore would offer more friction to the passage of the oil. Consequently the area of the cross-sectional area of the bore could be increased. The larger the cross-sectional area of the bore, the less liability there would be of the bore becoming clogged by dirt or foreign matter in the oil. The form of the invention as shown has been found to be satisfactory under ordinary operating conditions and has the advantage of low cost of manufacture.

While the invention has been described with considerable particularity of detail various changes may be made without departing from the spirit of the invention and consequently no limitations are included as may be defined by the appended claims.

What is claimed is:

1. In apparatus for lubricating air blowers by supplying oil to the air drawn in by the blower, the combination with the air intake of the blower, of an oil reservoir, an oil well, means for continuously feeding oil from the reservoir into said well, and a conduit leading from the bottom of said well to the air-intake whereby the suction produced in the air intake may draw the oil from the well into the ingoing current of air.

2. In apparatus for lubricating air blowers by supplying oil to the air drawn in by the blower, the combination with the air intake of the blower, of an oil reservoir, an oil well, means for continuously feeding oil from the reservoir into said well, a conduit leading from said well to the air-intake whereby the suction produced in the air-intake may draw the oil from the well into the ingoing current of air, an oil separator through which the air leaving the blower passes, and means for returning to said reservoir the oil collecting in the separator.

3. In apparatus for lubricating air blowers by supplying oil to the air drawn in by the blower, the combination with the air intake of the blower, of an oil reservoir, an oil well open to the atmosphere, means for feeding oil from the reservoir into said well, a conduit leading from said well to the air-intake whereby the suction produced in the air-intake may draw the oil from the well into the ingoing current of air, and means for supplying oil to said reservoir from an extraneous source to maintain a substantially constant oil level therein.

4. In apparatus for lubricating air blowers by supplying oil to the air drawn in by the blower, the combination with the air-intake and air-outlet of the blower, of an oil reservoir, means for feeding oil under sub-atmospheric pressure from the reservoir to the air-intake, and means in the air-outlet for separating the oil from the air.

5. In apparatus for lubricating air blow-

- ers by supplying oil to the air drawn in by the blower, the combination with the air-intake and air-outlet of the blower, of an oil reservoir of limited capacity, means for feeding oil from said reservoir to the air-intake, an oil reservoir of large capacity, means for feeding oil from the last-named reservoir to the air-intake, means in the air outlet for separating the oil from the air, and means for returning to the first-named reservoir the oil separated from the air whereby the oil supplied to the blower by the last-named reservoir replenishes the oil in the first-named reservoir. 40
6. In apparatus for lubricating air blowers by supplying oil to the air drawn in by the blower, the combination with the air intake and air outlet of the blower, of an oil well of relatively limited capacity, an oil reservoir, means for feeding oil from said reservoir to said well, a conduit through which the oil fed into said well passes to said intake when the blower is operating, a storage reservoir adapted to contain a relatively large supply of oil, a chamber of limited volume in said storage reservoir, means for feeding oil from the storage reservoir into the chamber therein, a conduit leading from said chamber to said intake, means associated with the air outlet of the pump for separating oil from air, and means for returning the oil separated from the air to the first-named reservoir. 45
7. In apparatus for lubricating air blowers by supplying oil to the air drawn in by the blower, the combination of means for initially flooding the blower with oil through the air intake and thereafter feeding oil thereto under the suction developed at the intake in amounts controlled independently of the speed at which the blower is operated. 50
8. In apparatus for lubricating air blowers by supplying oil to the air drawn in by the blower, the combination with the air intake of the blower, of an oil reservoir, an oil well open to atmosphere, means of restricted capacity for conveying oil from the reservoir to the well, and a conduit leading from the bottom of said well to the air-intake of the blower whereby the suction developed in the air intake may carry the oil from said well. 55
9. In apparatus for lubricating air blowers by supplying oil to the air drawn in by the blower, the combination of a reservoir, an open-top oil well located in the reservoir the bottom of the well being below the normal liquid level in the reservoir, an open passage through which oil may flow from the reservoir into the oil well, and means under the influence of the suction developed by the air drawn in by the blower for withdrawing the oil from the oil well and discharging it into the air passing through the blower. 60
10. The method of lubricating air blowers comprising initially flooding the blower with a slug of oil through the air intake, and thereafter feeding oil at a controlled uniform low rate into the air intake. 65
11. The method of lubricating air blowers comprising initially passing a slug of oil under blower suction into the blower along with the ingoing air, and thereafter feeding oil into the ingoing air at a uniform rate independently of variations in the speed at which the blower is operating. 70
